Inventor

Donald B Abbott
By his Attorney
Phillips Abbott.

UNITED STATES PATENT OFFICE.

DONALD B. ABBOTT, OF AUBURN, MAINE.

MOCCASIN.

Application filed August 18, 1922. Serial No. 582,576.

To all whom it may concern:

Be it known that I, DONALD B. ABBOTT, a citizen of the United States, and a resident of No. 98 Lake Street, in the city of Auburn, 5 county of Androscoggin, State of Maine, have invented certain new and useful Improvements in Moccasins, of which the following is a specification, reference being had to the accompanying drawings.

It is the purpose of this invention to simplify and reduce the cost of moccasins and particularly to eliminate certain objectionable features incident to footwear of the moccasin type. Among the advantages 10 secured by me are the following:—elimination of all seams over the ball of the foot thereby preventing ripping of the usual hand sewed seam at this point; the provision of a bandage around the instep of the foot thereby 15 affording a snug arch support; the division of the parts so that leather of different characteristics can be used at the points to which they are best adapted; reduction of the amount of puckering necessary around 20 the toe of the moccasin; the reduction of the amount of expensive hand sewing, and finally the retention of all the valuable features of the true moccasin construction.

Referring to the drawings it is to be noted 25 that they are not intended as patterns from which to cut the stock since the preferences of individual manufacturers may vary. Commencing at the heel of the shoe Fig. 1 represents a plan view (shown flat) of a backstay. Fig. 2 shows a plan view of the two quarters (shown flat), a backstay being 30 in position. Fig. 3 shows a plan view (shown flat) of the tongue provided with the so-called wings of my invention. Fig. 4 is 35 a plan view (shown flat) of the vamp. Fig. 5 is a plan view of the top of the moccasin as assembled without a sole. Fig. 6 is a plan view of the bottom of the moccasin as 40 assembled without a sole. Fig. 7 is an elevation of the moccasin as assembled with a middle sole attached and showing the outer 45 sole and heel in dotted lines.

In the drawings 1 (see Fig. 1) is the backstay. It is shown as of a conventional form 50 but may be of such shape as preferred. 2, 2 (see Fig. 2) are the two quarters, shown also as of conventional form, which may be varied as desired. The quarters are shown as stitched together along the dotted line 3 55 and the backstay 1 is shown as in position covering the seam 3. 4 (see Fig. 3) is the

tongue which it will be noted is of peculiar and unusual shape, that is to say it has the forwardly projecting tip, 5, of the ordinary moccasin, and the rearwardly projecting 60 loose member 6, but has added lateral members, 7, 7, the purpose of which will be hereinafter explained. 8 (see Fig. 4) is the vamp, the outline of the sole being indicated by the dotted line 9. In Fig. 5 the parts 65 above described are shown in top plan view as assembled, that is to say the upwardly and inwardly turned edges of the vamp 8 are shown as secured to the forwardly projecting tip 5 of the tongue, the quarters 2, 2 70 are shown in place around the heel with the backstay 1 in position, the loose tongue 6 is shown as resting between the forwardly projecting ends 10, 10 of the quarters, and the lateral members 7, 7 of the tongue are shown 75 as carried around beneath the moccasin at the instep section see Fig. 6 and attached along the line 11, 11 to the vamp and along the line 12, 12 to the forward ends of the quarters. In Fig. 6 the bottom of the moccasin (shown in plan view), similarly assembled, is shown, the ends of the lateral members 7, 7 being attached together under 80 the instep along the line 13. The lower turned in edges of the quarters 2, 2 and of 85 the counter 14 is shown. A lining is not shown since its use is optional. Fig. 7 shows an elevation of the moccasin similarly assembled but with a so-called "middle sole" 15 attached. An outer sole 16 and heel 17 90 (indicated by dotted lines) may be attached if desired.

I do not illustrate in the drawings, nor 95 describe, the stitching system of the moccasin (except to indicate the characteristic hand sewing which attaches the forward part of the tongue 5 to the forward part of the vamp 8) because that is well known to all makers of moccasins and moreover varies 100 according to the preferences of different makers.

It will be noted that because of the above 105 described peculiar construction of the moccasin I secure the following series of advantages, that is to say. The line of stitching 11, 11 which unites the tongue 7 to the vamp 8, is carried down under the foot so far forward of the point of flexure of the moccasin when in use, as to eliminate the tendency to break the stitches present in the 110 usual moccasin construction, at the point of flexure over the ball of the foot due to the

strain put upon them at that point. Also owing to the fact that the new laterally projecting members 7, 7 of the tongue are carried down under the instep of the foot and are preferably joined together along the line 13, I secure a snug bandage-like support for the arch of the foot. Also because of the peculiar shape of the tongue 5 and its laterally projecting members 7, 7 I am able to 10 use for it a less elastic leather (thereby preserving in use its shape and snug bandage-like support) than can be used for the vamp 8 which must be made of comparatively soft elastic leather in order to pucker properly 15 around the toe of the moccasin. Also owing to the unusual shape of the tongue 5 (i. e. its lateral projections 7, 7) in conjunction with the altered shape of the vamp 8, the edges of the parts along the line 11, 11 20 come smooth, and can be machine stitched except around the tip of the tongue 5, namely from about the point 18 to about the point 19. Between these points only will hand sewing be usually employed, so that 25 the puckering of the vamp may be effected in the usual manner, thus materially reducing the amount of expensive hand sewing as compared with the usual moccasin construction.

30 It will be noted from the foregoing that owing to my novel construction of the parts, I secure a series of very valuable results and still retain all the well-known advantageous features of the moccasin form of footwear, 35 including especially the fundamental moccasin characteristic, namely a continuous unbroken piece of leather under the ball of the foot and up the sides of the foot as in my vamp 8.

40 It will be obvious to those who are familiar with such matters that departures may be made from the details of construction described and illustrated by me and still the essentials of my invention and the 45 advantages secured by me be realized. I therefore do not limit myself in any respect to such details.

I claim—

1. A moccasin including a tongue, a vamp and quarters and in which the tongue member has laterally extending parts which extend downwardly under the instep section and separate the vamp from the quarters. 50
2. A moccasin including a tongue, a vamp and quarters and in which the tongue member has laterally extending parts which extend downwardly under the instep section and are joined together beneath the instep and which separate the vamp from the quarters at all points. 55
3. A moccasin including a vamp, quarters and a tongue stitched together at their meeting edges and in which the vamp and tongue member are so cut that the line of union between them is forward of the axis of flexure of the moccasin when in use. 60
4. A moccasin including a vamp, quarters and a tongue stitched together at their meeting edges in such a manner that no line of stitching crosses the axis of flexure of the 70 moccasin when in use.
5. A moccasin including a vamp, quarters and a tongue, the tongue and the vamp being so shaped that when their meeting edges are sewed together no stitching crosses the 75 axis of flexure of the moccasin when in use.
6. A moccasin including a vamp, quarters and a tongue so shaped that no line of union between any of its parts crosses the axis of flexure of the moccasin when in use. 80
7. A moccasin including a tongue, a vamp and quarters and in which the tongue member is interposed between the vamp and the quarters and constitutes a bandage surrounding the instep section of the foot of 85 the wearer.
8. A moccasin having quarters and a vamp and a continuous bandage-like part stitched to the quarters and also to the vamp and which entirely surrounds the instep section of the foot of the wearer. 90

Signed this 3rd day of August, 1922.

DONALD B. ABBOTT.
